UNITED STATES PATENT OFFICE.

LOUIS MARKOWITZ, OF NEW YORK, N. Y.

DESIGN FOR A BADGE.

53,076.

Specification for Design. Patented Mar. 11, 1919.

Application filed November 14, 1918. Serial No. 262,608. Term of patent 7 years.

To all whom it may concern:

Be it known that I, LOUIS MARKOWITZ, a citizen of the United States, and resident of the borough of Manhattan, city, county, and State of New York, have invented a new, original, and ornamental Design for Badges, of which the following is a specification, reference being had to the accompanying drawing, forming a part thereof.

The figure is a face view of a badge showing my new design.

I claim:

The ornamental design for a badge substantially as shown.

Signed at New York, county and State of New York, this 12th day of November, 1918.

LOUIS MARKOWITZ.
